UNITED STATES PATENT OFFICE.

ISABEL LIKENS GATES, OF WASHINGTON, DISTRICT OF COLUMBIA.

GARMENT SUPPORT.

Application filed March 21, 1923. Serial No. 626,592.

To all whom it may concern:

Be it known that I, ISABEL LIKENS GATES, a citizen of the United States, residing at Washington, District of Columbia, have invented certain new and useful Improvements in Garment Supports, of which the following is a specification.

The invention relates to camisoles, brassières, ladies' lingerie, dresses or similar articles of apparel which are supported or hung from the shoulders of the wearer, and more particularly to the provision of means for supporting a garment of this character in such a manner as to obviate the tendency of such supporting means to slide off from the shoulders of the wearer and at the same time having said means contracting or gathering certain parts of said garment.

A further object of the invention is the provision of means for supporting a garment and comprising a strap, tape or ribbon formed preferably from a single continuous piece, and which can be very readily applied or removed when the garment is to be laundered or a new string utilized and which will be attractive in appearance.

Illustrative embodiments of the invention are shown in the accompanying drawing, in which—

Fig. 1 is a perspective view of the garment on a wearer's body with the supporting means in place.

Figs. 2, 3 and 4 are plan views of three forms of the invention with the garment omitted.

Figs. 5, 6, 7, 8, and 9 are plan views of different forms of the invention with the garment omitted.

Reference is made to the applicant's co-pending application, Serial No. 622,946, filed March 5, 1923, wherein is disclosed two types of garments having their upper portions provided with certain means by which the supporting means are attached to the garments. The garments disclosed therein are hereby made a part of this application and the supporting means disclosed in this application may be used with the types of garments set forth in that application.

As shown in Fig. 1 the upper garment portion 1 is provided with a suitable tubular or draw string receiving portion 2 extending completely around the top of the garment tho it may be omitted at certain parts of the front or back of the garment

while in all the present forms the arm-pit portions of the garment are provided with these suitable receiving means.

In Figs. 1 and 2 the device preferably comprises a continuous strap ribbon, tape or cord having a portion 4 threaded thru and slidably engaging the front upper edge of the garment from a point adjacent and in front of one shoulder to a point adjacent and in front of the other shoulder. Portions 5 and 6 of the ribbon are then passed upwardly and rearwardly over the shoulders and enter the garment at points adjacent and in back of the shoulders of the wearer. The ribbon portions 7 and 8 are then threaded or woven thru the opposite arm-pit portions of the garment around toward the front and continue thru the front edge of the garment until they reach the front center of the garment thereby forming the front engaging portions 9 and 10. The ends 11 and 12 are then tied, bowed or suitably secured to each other as at 13.

From the drawing it will be seen that Fig. 3 differs from Fig. 2 in that instead of having the shoulder strap portions 5 and 6 connected together by the continuous portion 4 they are connected by the portions 14 and 15 carrying respectively the tape ends 16 and 17 which may be suitably tied together and instead of having the arm-pit engaging portions 7 and 8 connected by portions 9 and 10 they are connected by a continuous front engaging tape portion 18.

The modification shown in Fig. 4 differs from that shown in Fig. 2 in that the portions 9 and 10 are omitted and the tape terminates in ends 19 and 20 situated at points adjacent and in front of the wearer's shoulders where they may be suitably connected or fastened to the garment as by tying, pinning or stitching.

The form shown in Fig. 5 comprises a plurality of shoulder strap portions 21 and 22, a plurality of rear engaging portions 23 and 24, a plurality of front engaging portions 25, 26 and 27, and a plurality of arm-pit engaging portions 28 and 29. The portions 23 and 24 extend across and are threaded thru the back of the garment, the portions 25, 26, and 27 extend across and are threaded thru the front of the garment and the portions 28 and 29 extend thruout and are threaded thru the arm-pit portions of the garment while all of these portions en-

gage their respective garment parts in slide-
able fashion.

Fig. 6 differs from Fig. 5 in that instead
of having the portions 26 and 27 the shoul-
der straps 21 and 22 terminate in tape ends
30 and 31 which are preferably secured to
the garment in a manner and place similar
to the ends 19 and 20.

Fig. 7 differs from Fig. 5 in that instead
of having the shoulder straps 21 and 22 connected
by two separated portions 26 and 27 they are connected by a continuous portion
39 while instead of having the arm-pit portions
28 and 29 connected by a continuous
portion 25 they are connected by separated
portions 40 and 41 carrying the tape ends
42 and 43 which may be secured together as
at 13.

In Fig. 8 the portions 44, 45 and 46 en-
gage and are threaded thru and across the
back upper portion of the garment; the portions
47, 48, 49 and 50 engage and are
threaded thru and across the front upper
portion of the garment; the portions 51 and
52 engage and are threaded thru the arm-
pit portions of the garment while two pairs
of shoulder strap portions 53, 53^a, and 54,
54^a, extend up over the shoulders in the
manner shown in the drawing. The ribbon
ends 55 and 56 may be fastened in a manner
similar to that as at 13.

The form shown in Fig. 9 omits the por-
tions 49 and 50 and has the shoulder straps
53^a and 54^a directly connected to each other
35 by the separated front engaging portions
57 and 58 and instead of having the portions
51 and 52 directly connected by the portions
47 and 48 they are directly connected to the
portions 53 and 54.

40 It will be noted that the shoulder strap
portions in Figs. 5, 6, 7, 8 and 9 are in par-
allel planes while in Figs. 1, 2, 3 and 4 at
least the front portions of the shoulder strap
portions are in parallel planes.

45 It is found that a strap formed of a rib-
bon preferably continuous and positioned as
described is very comfortable to wear and
has no tendency to slip off the shoulders,
thus relieving the wearer of the necessity of
50 awkward, and embarrassing movements re-
quired to replace the ordinary forms of sus-
pension means in position.

A further advantage of this garment sup-
port consists in the fact that it avoids the
55 tearing of the garment to which it is at-
tached, it yields with the movements of the

wearer and draws and contracts certain
parts of the garment to the body.

Minor changes may be made in the phys-
ical embodiment of the invention without
departing from its spirit.

I claim:

1. In combination with a garment having
a front portion, a back portion and arm-pit
portions, a continuous support having a sec-
tion threaded through and slidably engag-
ing one of said portions, sections threaded
through and slidably engaging said arm-pit
portions and one or more sections adapted to
extend across each of the wearer's shoulders
with all of the parts of said shoulder sec-
tions on one side of the wearer's body in par-
allel planes when the garment is in worn
condition.

2. In combination with a garment having
a front portion, a back portion and arm-pit
portions, a continuous support having a plu-
rality of sections threaded through and slid-
ably engaging one of said portions, sections
threaded through and slidably engaging
said arm-pit portions and one or more sec-
tions adapted to extend across each of the
wearer's shoulders with all of the parts of
the said shoulder sections on one side of the
wearer's body in parallel planes when the
garment is in worn condition.

3. In combination with a garment hav-
ing a front portion, a back portion and arm-
pit portions, a continuous support having a
section threaded through and slidably en-
gaging one of said portions, sections thread-
ed through and slidably engaging said arm-
pit portions with the other portion of said
garment free of said support.

4. In combination with a garment having
a front portion, a back portion and arm-pit
portions, a continuous support having a plu-
rality of sections threaded through and slid-
ably engaging one of said sections, sections
threaded through and slidably engaging said
arm-pit portions with the other portion of
said garment free of said support.

5. In combination with a garment having
a front portion, a back portion, and arm-pit
portions, a continuous support having a sec-
tion threaded through and slidably engag-
ing one of said portions, sections adapted to
extend over a wearer's shoulders, and sec-
tions threaded through and slidably engag-
ing said arm-pit portions with the other por-
tion of said garment free of said support.

ISABEL LIKENS GATES.
